Primary Examiner — Jeffrey D Asch**CLAIM**

The ornamental design for an electronic device, as shown and described.

DESCRIPTION

FIG. 1 is a front perspective view of an electronic device; FIG. 2 is a rear and bottom perspective view thereof; FIG. 3 is a front elevation view thereof; FIG. 4 is a rear elevation view thereof; FIG. 5 is a right side elevation view thereof; FIG. 6 is a left side elevation view thereof; FIG. 7 is a top plan view thereof; and, FIG. 8 is a bottom plan view thereof.

The outermost broken lines that are immediately adjacent to the claimed surfaces represent the boundaries of the claim. All other broken lines show portions of the electronic device that form no part of the claimed design. The broken lines form no part of the claimed design.

1 Claim, 6 Drawing Sheets(56)
